UNITED STATES PATENT OFFICE.

DANIEL F. LANE, OF CORNING, NEW YORK.

TRUSS-BRIDGE.

SPECIFICATION forming part of Letters Patent No. 531,048, dated December 18, 1894.

Application filed April 8, 1892. Renewed April 7, 1894. Serial No. 506,775. (No model.)

To all whom it may concern:

Be it known that I, DANIEL F. LANE, a citizen of the United States, residing at Corning, in the county of Steuben and State of New York, have invented certain new and useful Improvements in Truss-Bridges, of which the following is a specification.

I have improved the construction of the truss-bridge for which Letters Patent No. 424,318 were granted to me March 25, 1890, and my present improvements are directed to provisions whereby the connections of the floor-beams and the top truss-beams are rendered stronger and more durable; the floor truss-rods rendered more effective; the abutments for the ends of the bridge rendered durable and firm; and the bridge rendered stiff and firm. In these particulars my invention consists of certain parts and combinations of parts, the several features of which will be separately pointed out in the claims concluding this specification. Before specifying such claims I will describe the bridge which is illustrated in the annexed drawings, showing a structure embodying the several features of my present invention in combination.

Referring to the drawings: Figure 1 is a side view of an iron bridge constructed according to my invention. Fig. 2 shows a side view of the iron abutment for the bridge. Fig. 3 is a top view of the bridge shown in Fig. 1. Fig. 4 shows in vertical sectional elevation the lapped end of the abutment cap-beam and the ends of the truss beams secured thereon and together, one-half of the clamping chair being removed, and Fig. 5 is an end view of the same. Fig. 6 shows in side view a coupling binder for connecting the upper truss beam with its central arched brace. Fig. 7 is a vertical cross section on the line z of Fig. 6, and Fig. 8 shows one of the coupling binder parts. Fig. 9 is a top view of the iron abutment. Fig. 10 is a horizontal section of one end of the abutment on the line y of Fig. 4, showing the manner of securing the cap beam to the abutment piles. Fig. 11 shows one of the divided chair parts for the chord beams. Fig. 12 is a shoe block for connecting the girder beam and its truss rod. Fig. 13 is a vertical cross section on the line x of Fig. 14, which is a vertical sectional elevation showing the lower truss beam, the girder

beam, its shoe block truss-rod connection, and the top truss-beam clip connections with the girder-beam. Fig. 15 shows the brace rod connection with the top truss-beam, and Fig. 16 shows a construction in which the floor girders are extended beyond the truss beams to form side walks at each side of the bridge.

The two horizontal truss-beams 1, the top truss-beams 2 and 3, and the cross or girder-beams 4, I prefer to make of railroad iron. The lower truss-beams are the length of the bridge and rest at their ends upon pile abutments which are also preferably of railroad iron, and the truss-beams are secured together, and to these pile abutments at the ends of the bridge, as I shall presently state. In forming the abutments I drive a row of iron piles 5 along or near each bank so that their flanges 6 stand toward the water, as seen in Figs. 9 and 10, and they are sufficiently close together to form a firm support on which the bridge rests with its flooring on a level with the roadway. A cap-beam 7 preferably of angle or L-shaped iron is placed upon the tops of the piles so that its vertical side abuts against the flange 6 of the piles, and is secured and bound thereto by clips 8, see Fig. 4, passed around the piles and through holes in the vertical side of the cap-beam 7 and fastened by nuts 9. The ends of this cap beam are bent and turned inward toward the bank so as to form a lap 10, which I secure to one or two piles 11 in the same manner as with the row of piles. On the land side I cover the row of piles with iron plates 12 so as to form a wall, and I fasten these wall plates to the rows of piles by nutted clips 13. On the water side I secure to the row of piles one or more beams 14, preferably of railroad iron, extending obliquely from the lower end of one pile at one end of the row to the upper end of the pile at the other end of the row, and inclining down the river and I fasten this inclined beam to the piles by nutted clips 15. This construction provides a pile abutment of iron so as to form a structure walled and braced and a solid sill or foundation for the ends of the chord-beams at each end of the bridge.

A base plate 16 is (seen in Figs. 4 and 5) placed across the lapped ends of the cap beam 7 and forms the seat for the end of the

truss-beam 1 and to which it is secured by a chair of peculiar construction which I will now describe. An iron chair the counterpart of the truss-beam, is provided so as to form a clamp, preferably of two parts 17, adapted to fit over and upon the end of the truss-beam, each part having a base flange 18 by which it is secured to the base plate 16 by the nutted bolts 19. A nutted bolt 20 passing through the chair parts and the web of the truss beam, and a nutted bolt 20^a passing through the chair parts above the latter bind the chair parts and said beam together. A nutted clip 21 passing in a groove over and upon the chair parts and through holes in the cap-beam of the abutment, serves to secure and bind the chair parts to the said abutment. Each end of each truss beam is supported and secured in an identical way. Centrally at the middle 20 of the length of the bridge and at equal distances therefrom I secure cross beams or girders 4 beneath the truss-beams by means of nutted clips 23, see Fig. 14, passed over the said beams and through holes in a base-plate 24 on the under side of the girder, the clips obliquely straddling the girder.

The truss beams 2 are inclined downward at their ends and are fitted into sockets 25, see Fig. 11, formed at the inner ends of the divided chair parts 17, which chair parts thereby serve as abutments for the truss-beams. This socket is the counterpart of the truss-beam 2 and the latter when bound therein rests in a shouldered notch *c* upon the head or ball of the lower truss-beam. The head or ball of the lower truss-beam is notched and upset at 26, see Fig. 4, and the chair parts have corresponding notches and projections 26, see Fig. 11, which interlock and 40 supplement the fastenings of the chair parts for resisting the thrusting action of the truss-beams 2 upon the divided chair. At these abutting ends I fasten the truss-beams together by nutted clips 27 straddling the beams and passing through the projecting ends of a tie-rod 28 beneath the lower truss beam, as in Fig. 4. The chair socket and the clip serve to hold the end of the upper truss-beam firmly and solidly upon the lower truss-beam and 50 prevent it from side movement as the chair embraces the truss-beams like a clamp.

Referring to Fig. 4 it will be seen that the lower truss-beam is notched and upset at *c* to receive the end of the upper truss-beam and form a shouldered abutment therefor and that the corners *c*² of the base of the latter beam are turned down at the ends so as to lap on each side of the ball or head of the lower truss-beam, and thus give a firm support for each end of the upper truss-beam in connection with the abutting chair of the lower truss-beam, and the clips 27 which straddle both beams.

The upper truss-beams and the girder-beams are connected by rods 29 secured by nuts 30 to the base-plate 24, and by nuts 31 to the angle plates 32 which are bolted to the

opposite sides of the upper truss-beam; said rods being preferably crossed as shown in Figs. 1 and 14. At the middle of the span 70 an arched truss brace 3 supports the main upper truss-beam and is clipped at its ends to the lower truss-beam, which latter is upset to form abutments 33 for the brace. At the junction of the arch and upper truss-beam, 75 clip-rods 34 straddle these beams and are nutted to the girder base plate 24. I find it important however to connect the arch and upper truss-beam to give the latter a better support, and for this purpose I provide a 80 binder of two clamping parts 35 having their clamping faces the counterparts of the railroad iron form of these joining parts, as seen in Figs. 7 and 8, so that the binders will lie upon the webs of these parts and be bound firmly thereon by clinch bolts 36. The clip-rods 34 pass over these binder parts 35 in face grooves 37 which serve to hold the rods in place.

A truss-rod 38 is placed beneath each girder and is secured to each of its ends by a shoe or socket block 39 as seen in Figs. 1, 12 and 14, and is trussed over a downward standing post or prop 40 at the middle of the girder. The shoe is a solid iron block cast with sockets 41 the counterpart of the cross section of the beam and it has a bottom projection 42 by which it is bolted to the base flanges of said beam. The truss-rod passes through holes in the shoe blocks and is secured by nuts 43 with which I use washers 44 seated in a concave bearing in the outer end of the shoe so that the latter form solid abutments for the rod and with the latter and the middle prop, form a durable and effective support for the girder-beam. One or more brace rods 45 connect and are nutted to each end of the girder-beam and to the inclined ends of the upper truss beam, through the web of which it passes and rests upon a wear plate 46 as seen in Fig. 15. 110 Brace rods 47 connect the girder-beams with the abutments through the truss beam plates 16, to which said rods are secured by the studs 48, as seen in Figs. 3 and 5; while one or more tie rods 49 connect the girders to each other. 115

Where the clip fastenings pass over the edges of the flanges of the beams, the latter are notched to give a positive locking connection therewith.

In Fig. 16 I have shown a construction of 120 the girder-beams for side walks in which the said girder-beams are extended to give the desired width of walk, and in this connection I do not use the bottom truss-rods.

The construction which I have set out gives 125 a strong, safe and durable iron bridge for comparatively short spans. The floor-girders and the truss-beams are bound together by rod-clips; the flooring structure is firmly braced; and the truss-beams, and the abutments are bound together by bolts and clip-rods. At this abutment connection the construction of the abutments gives a broad and solid support for the truss-beams; and the

doubled or lapped ends of the abutments, give the advantage of firmness which would be given by a double abutment.

The provision of the abutment chairs gives great strength and firmness at the connection of the truss-beams, and a strength capable of resisting great weight at the center of the bridge; and the construction is in every way rendered stiff and firm against longitudinal or lateral vibration; or sinking at the crown. It is obvious that the abutments can be placed to form a wall at the bank or a short distance away from the bank; and that the piles when firmly driven, walled and braced, form a structure more durable as a support for the end of the bridge, than would be afforded by stone work or piles alone. It is evident that immaterial departures may be permitted from the general construction and arrangement of parts contributing toward my invention, and for this reason I do not wish to be understood as limiting myself thereto in precise detail, and construction.

Referring to Fig. 14 it will be seen that the girder-beams 4 and the truss-beams 2 are connected by rods 29 nutted to plates 24 under the girder-beam and to angle-plates 32 bolted to the opposite sides of the truss-beams, and it will be understood that these angle-plates 30 are fitted upon the web and base of said truss-beam and are bolted to said web through their vertical sides, while the said rods are nutted to the horizontal sides of said angle-plates, which, for this purpose, overhang the 35 edges of the beam, and thereby give a strong and durable fastening for these rods to separate plates at both ends. It will also be understood that the plates 24 project on each side of the girder-beams and that these rods 40 are arranged in pairs on each side of said beam, as seen in Fig. 3.

Having thus described an iron bridge embodying, in preferred form, the several features of my present invention in combination, 45 what I claim, and desire to secure by Letters Patent, is—

1. In an iron bridge, the combination, of an abutment and the truss beams, the upper beam resting upon and engaging the lower beam, with a chair formed of two matching parts engaging the lower beam, the bolts 20, 50 20^a securing the chair parts together and to the lower beam, the nutted clip 27 engaging said beams, and the nutted clip 21 engaging the chair and the abutment, substantially as described.

2. The combination, in an iron bridge, of the truss-beams, with chairs formed of two counterparts providing sockets or seats adapted to 60 receive and support the ends of said beams in abutting relation, and nutted bolts 20 and 20^a passing through the beam and the chair parts, substantially as described.

3. The combination, in an iron bridge, of the truss-beams, with chairs formed of two counterparts providing sockets or seats adapted to receive and support the ends of said beams

in abutting relation, a base plate 16, a transverse abutment beam, and means for binding and securing said parts together, substantially 70 as described.

4. The combination, in an iron bridge, of the truss-beams, with chairs formed of two counterparts provided with sockets or seats adapted to receive and support the ends of 75 said beams in abutting relation, a base-plate 16, a transverse abutment beam, bolts for securing the chair, plate and said beams together, a clip for securing the chair, plate and abutment beam together, and a clip for securing the chord and truss-beams together, substantially as described.

5. The combination, in an iron bridge, of the truss-beams, with a binder chair support for their ends, an abutment formed of a beam 85 bent and lapped at its ends, and means for binding and securing the said several beams and chair parts together, substantially as described.

6. The combination, with the truss-beams 90 and a chair provided with seats or sockets adapted to receive and support the ends of said beams, of a base-plate for said chair, and a transverse cap-beam bent and lapped at its ends, means for securing said chair to said 95 base-plate, and means for securing said chair, base-plate and lower beams to the lapping end of said cap-beam, substantially as described.

7. The combination, in an iron bridge, of the truss-beams, with a chair formed of two counterparts having sockets or seats adapted to receive and support the ends of said beams in abutting relation, the ball or head of the truss-beam and the wall of the chair-socket 100 having engaging upset parts, and means for 105 binding the said beams together and to the chair parts, substantially as described.

8. In an iron bridge, an abutment chair of two half parts, each part having a base side flange 18, an end socket 25 and notches and 110 projections 26 on its inner wall, in combination with the lower flanged truss beam having notches and projections corresponding with those of the chair-walls, and means for 115 binding the parts together and to the said lower beam, substantially as described.

9. The combination, in an iron bridge, of the floor or girder-beams, with the truss rod and the shoe or socket-blocks for connecting the ends of said truss rod and the girder-beam, 120 substantially as described.

10. The combination, in an iron bridge, of the floor or girder-beams, and the truss-beams, with the shoe or socket-blocks, the truss-rod, the base plates 24, and the clips 23 and 29, 125 substantially as described.

11. The combination, in an iron bridge, of the main and the arch truss-beams, and the floor or girder-beams, with the clamps or binders 35, the base-plates 24, and the clips 23 and 130 34, substantially as described.

12. The combination, in an iron bridge, of the floor or girder-beams, the truss-beams, and the base-plates 24, with the clamps or bind-

ers 35, the clips 29 and 34, and the brace-rods 45, substantially as described.

13. The combination, in an iron bridge, of the truss-beams, and the floor or girder-beams, 5 with the base-plates 16 for said truss-beams, chairs or binders provided with sockets or seats adapted to receive and support the ends of the truss-beams, the brace rods 47 connecting the said base-plates and girder-beams, 10 and means for binding and securing the said truss-beams, chairs and base-plates together, substantially as described.

14. In combination, in an iron bridge, the truss-beams, the socket chairs and the arch 15 clamps or binders therefor, the floor or girder-beams, their truss rods and shoe or socket-blocks, the clips and brace rods, and iron abutments having cap-beams bent and lapped at their ends and bound and secured to the 20 said socket chairs, substantially as described.

15. The combination, in a bridge, of the truss-beams and the arch-beams, with clamps or binders having their clamping sides formed 25 with grooves interlocking with the flanges of the truss-beam and the sides of the head of the arch-beam, and riveted to the webs of both said beams, substantially as described.

16. The combination, in an iron bridge, of the truss-beams and the girder-beams, the 30 rods 29 connecting the truss and girder-beams by the base plates 24 and by the angle plates 32 bolted to each side of the web of said truss beam, substantially as described.

17. The combination, in an iron bridge, of 35 the truss-beams and the base-plates 16, with a sectional flanged chair 17 constructed to form the socket for the end of the truss-beam, a nutted clip 21 and the bolts 19, 20 and 20^a for securing the parts together, substantially 40 as described.

18. The combination, in an iron bridge, of the lower chord having the notched abutments 26 and c in its head, with a sectional chair-socket constructed to engage the beam abutment 26, the truss-beam engaging the 45 beam abutment c and means for securing said parts together, substantially as described.

19. The combination, in an iron bridge, of the truss-beams, and the girder-beams, with sectional chair sockets constructed to engage 50 said truss-beams, the base plates 16, means for securing the latter to the sectional chair, means for securing the latter to the truss-beams, and the brace rods 47 connecting the said base-plates and girder-beams, substantially 55 as described.

20. As a tie and support for the lower chord-beams of an iron bridge, the horizontal cap-beams of angle iron bent and lapped at each 60 end, in combination, with the truss-beams, and suitable means for securing the ends of said beams to said cap-beams, substantially as described.

21. The combination, in an iron bridge-truss, of a tie-beam and a brace-beam of rail-way T rail, with chairs formed of two parts 65 with confronting faces, each face conforming in contour to the said beams and having a shoulder to receive the abutting end of the brace-beam and bolts for securing said parts 70 of the chair to each other, and to the tie-beam, substantially as described.

In testimony whereof I have hereunto signed this specification in the presence of witnesses.

DANIEL F. LANE.
